(57) **CLAIM**

The ornamental design for a cooking apparatus, as shown and
described.

DESCRIPTION

FIG. 1 is a front, left side perspective view of a first embodiment
of a cooking apparatus of the present invention;

FIG. 2 is a front elevational view thereof;

FIG. 3 is a rear elevational view thereof;

FIG. 4 is a top plan view thereof;

FIG. 5 is a bottom view thereof;

FIG. 6 is a left side elevational view thereof; and

FIG. 7 is a right side elevational view thereof;

FIG. 8 is a front, left side perspective view of a second
embodiment of a cooking apparatus of the present invention;

FIG. 9 is a front elevational view thereof;

FIG. 10 is a rear elevational view thereof;

FIG. 11 is a top plan view thereof;

FIG. 12 is a bottom view thereof;

FIG. 13 is a left side elevational view thereof; and,

FIG. 14 is a right side elevational view thereof.

The details shown in broken lines form no part of the claimed
design.
